I. N. COOPER,
FIRE EXTINGUISHER FOR OIL TANKS AND THE LIKE.
APPLICATION FILED DEC. 8, 1919.

1,349,048.

Patented Aug. 10, 1920.

Attorney

UNITED STATES PATENT OFFICE.

ISAAC N. COOPER, OF FORT WORTH, TEXAS.

FIRE-EXTINGUISHER FOR OIL-TANKS AND THE LIKE.

1,349,048.

Specification of Letters Patent. Patented Aug. 10, 1920.

Application filed December 8, 1919. Serial No. 343,410.

To all whom it may concern:

Be it known that I, ISAAC N. COOPER, a citizen of the United States of America, residing at Fort Worth, in the county of

5 Tarrant and State of Texas, have invented certain new and useful Improvements in Fire-Extinguishers for Oil-Tanks and the like, of which the following is a specification.

10 My invention relates to fire-extinguishers, and more particularly to fire-extinguishers for stopping the burning of oil in oil tanks; and the object is to provide simple devices for stopping instantly a fire which is burning 15 in an oil tank and to provide devices which are simple in construction and operation and which will involve relatively small expense in making and installing. Other objects and advantages will be fully explained 20 in the following description and the invention will be more particularly pointed out in the claims.

Reference is had to the accompanying drawings which form a part of this application.

25 Figure 1 is a side elevation of an oil tank equipped with the improved fire-extinguisher. Fig. 2 is an enlarged sectional view, showing the means for effecting a suction. Fig. 3 is a plan view of the gearing and fans for effecting the suction. Fig. 4 is a similar view, but showing a variation in the gearing. Fig. 5 is a detail view of the driving gear.

30 Similar characters of reference are used to indicate the same parts throughout the several views.

One of the necessary arrangements in the installing of the fire-extinguishing apparatus is to mount the roof 1 of the oil tank above the top 2 of the wall of the tank. The object is to have the roof or cover 1 spaced from the tank wall so that air will pass under the roof. The fire will be drawn 45 away from the oil by suction and the suction is created by revolving fan blades. A hood 3 is mounted on top of the roof 1 which has an opening 4 in the central part or at the apex of the cone-shaped roof. Bars 5 and 6 are secured in the hood 3 and a shaft 7 is journaled in the bars 5 and 6. Fans 8, 9, and 10 are made rigid with the shaft 7. The fans are driven by a motor 11 which may be located at any suitable place. 50 A sprocket chain 12 is driven by the motor 11 and this chain drives a bevel gear wheel

13 which may be integral with a gear wheel 14. The wheel 13 drives a bevel gear wheel 15 which may be integral or rigid with a gear wheel 16. The gear wheel 16 drives a 60 chain 17. The chain 17 drives a gear wheel 18 which is rigid with shaft 7 which drives the fans. When the fans are driven, there will be a suction created above the central part of the tank. The hood 3 may be supported on bars 19 which are supported on upright posts 20. The roof 1 is supported above the top edge 2 of the tank by stays 21. A pipe 22 may be used to conduct the draft to any suitable distance. The draft 70 will carry away all gases and so remove the main cause of the fire and the flame will be gathered or drawn away by the suction and extinguished.

This invention is useful for extinguishing 75 fires at oil tanks, turpentine and varnish refineries, cotton seed oil mills, and also in packing houses where there are oil reservoirs, and in other places where there are inflammable liquids.

80 What I claim, is,—

1. A fire-extinguishing apparatus in combination with a tank containing an inflammable material and provided with a cone-shaped cover spaced from the tank and extending radially outward beyond the edge of the tank and having an opening through the apex of the cover, and means for producing a draft radially inwardly between the cover and the tank and through said 90 opening for driving flames away from the interior of said tank.

2. A fire-extinguishing apparatus comprising a hood placed on a vessel containing inflammable material and having communication therewith, means for permitting air to flow in said vessel, a vertical shaft journaled in said hood, one or more sets of fan blades rigid with said shaft, means for driving said shaft, and a pipe connected to 100 said hood for conveying away the draft created by said fan blades.

3. A fire-extinguishing apparatus in combination with a tank containing an inflammable material and provided with a cone-shaped cover spaced from said tank and having an opening at the apex of the cover, a hood mounted on said cover and communicating with said tank through said cover, a discharge pipe connected to said 110 hood, and means for creating suction through said hood.

4. A fire-extinguishing apparatus in combination with a tank containing an inflammable material and provided with a cone-shaped cover having an opening at the apex thereof, means for spacing said cover from the edge of the tank, a hood mounted on said cover and covering said opening, a dis-
- 5

charge pipe connected to said hood, and means for creating a suction draft in said hood.

In testimony whereof, I set my hand, this 3rd day of December, A. D., 1919.

10

ISAAC N. COOPER.
